MAGNETO POST.

Application filed May 26, 1925. Serial No. 33,021.

This invention relates to magneto binding posts and more particularly to a magneto binding post of the type employed in a well known construction of magneto wherein the 5 magneto is embodied in the engine structure.

In this type of magneto, the field coil plate is stationary and is confronted by a rotating plate bearing permanent magnets. The entire magneto construction is inclosed 10 in a housing which also serves to house the fly wheel of the engine, the transmission and to form an oil reservoir. The rotating permanent magnet carrier dips into this oil reservoir and consequently often picks up 15 small bits of metal or lint from the reservoir. One side of the field coils is grounded and the other side thereof is led to a contact on the upper surface of the plate and confronting an opening formed through the 20 housing. Seated upon the housing at the opening and projecting through the opening is a magneto contact post which, in the ordinary type of construction, embodies a spring pressed contact element which 25 engages the contact element of the coil plate. In the operation of the engine, the vibration often causes a slight separation of this spring pressed contact and the contact of the coil plate and furthermore this vibration permits lint to collect beneath the contact point with the result that the contact point is often insulated and permits bits of 30 metal to gather which often have a tendency to short circuit the contact point. Accordingly 35 an important object of this invention is the provision of a magneto post of such character that insulation thereof from the coil plate contact may not occur and which is furthermore of such structure that the 40 magneto contact may be fully protected against short circuiting.

A still further object of the invention is to provide a device of this character which may be left attached to the magneto cover 45 plate when the same is removed and replaced, thereby avoiding the now necessary operation of removing this binding post each time that the cover plate is removed.

These and other objects I attain by the 50 construction shown in the accompanying drawings, wherein for the purpose of illustration is shown a preferred embodiment of my invention and wherein:—

Figure 1 is a vertical sectional view 55 through a magneto showing a magneto post

constructed in accordance with my invention applied thereto;

Figure 2 is a section on the line 2—2 of Figure 1.

Referring now more particularly to the 60 drawings, the numeral 10 generally designates the coil plate of the magneto and 11 the contact of this coil plate and 12 a housing for the magneto having an opening 13 aligning with the contact 11 of the magneto. The binding post employed consists of an insulating body 14 carrying a collar 15 adapted to be attached to the housing at the sides of the opening 13. At its upper 65 end, this body has a binding post 16 communicating with a bore 17 formed in the body and having arranged therein a filling of preferably soft conducting material 19. Through this filling extends a bore 20, the lower end of which together with the housing 14 combine to produce a conical mouth 21 leading to the bore. Through the wall of the body and the metal 19 a set screw 22 is directed, the inner end of which enters 70 the upper end of the bore.

Secured to the contact 11 is a conductor 23 of sufficient length to extend approximately to the upper end of the bore 20. The lower end portion of this conductor is insulated, as at 24, and, if desired, this insulation may extend over the binding post or contact 11 of the magneto coil plate 10, as indicated at 25.

In the use of the device, the conductor 23 is vertically disposed and in replacing the 80 cover engages in the funnel mouth 21 of the bore 20 and is directed into this bore. After the cover plate has been fully seated, the set screw 22 is moved inwardly until it 85 engages the upper end of the conductor 23 and forces the same solidly into contact with the soft metal filling 19.

By this structure, a very firm contact is maintained at all times. The conductor 23 being soldered to the contact 11 may not 90 separate therefrom by vibration during operation of the engine and the insulation will effectively prevent the collection of bits of metal which will tend to short circuit this contact. At the upper end of the chamber, 105 of course, a firm mechanical as well as an electrical bond is provided between the core 19 and the contact.

Since the structure hereinbefore set forth is obviously capable of a certain range of 110

change and modification without materially departing from the spirit of my invention, I do not limit myself to such specific structure except as hereinafter claimed.

5 I claim:—

1. In combination with a magneto having a contact, a housing within which the contact is arranged and having an opening, a magneto post secured to the housing and extending into the opening, a conductor permanently secured at its lower end to the contact of the magneto, said post being formed of insulating material and having a metallic core provided with a bore into which the upper end of the conductor may extend, means for firmly seating the upper end of the conductor against the wall of the bore and a binding post for the magneto post electrically connected with said core.
- 10 2. In combination with a magneto having a contact, a housing within which the contact is arranged and having an opening, a magneto post secured to the housing and extending into the opening, a conductor permanently secured at its lower end to the contact of the magneto, said post being formed of insulating material and having a metallic core provided with a bore into which the upper end of the conductor may extend, means for firmly seating the upper end of the conductor against the wall of the bore and a binding post for the magneto post electrically connected with said core.
- 15 3. In combination with a magneto having a contact, a housing within which the contact is arranged and having an opening, a magneto post secured to the housing and extending into the opening, a conductor permanently secured at its lower end to the contact of the magneto, said post being formed of insulating material and having a metallic core provided with a bore into which the upper end of the conductor may extend, means for firmly seating the upper end of the conductor against the wall of the bore and a binding post for the magneto post electrically connected with said core.

end of the conductor against the wall of the bore and a binding post for the magneto post electrically connected with said core, the lower end of the magneto post and said core being formed to provide a funnel mouth directing the upper end of the conductor into the bore of the metallic core.

3. In combination with a magneto having a contact, a housing within which the contact is arranged and having an opening, a magneto post secured to the housing and extending into the opening, a conductor permanently secured at its lower end to the contact of the magneto, said post being formed of insulating material and having a metallic core provided with a bore into which the upper end of the conductor may extend, means for firmly seating the upper end of the conductor against the wall of the bore and a binding post for the magneto post electrically connected with said core, the lower end of the magneto post and said core being formed to provide a funnel mouth directing the upper end of the conductor into the bore of the metallic core, the magneto contact and said conductor beneath said magneto post being insulated.

In testimony whereof I hereunto affix my signature.

LAFAYETTE LINTECUM.
